Robt J. Sprague

UNITED STATES PATENT OFFICE.

J. HILL WHITING, OF DETROIT, MICHIGAN.

CUPOLA-FURNACE.

SPECIFICATION forming part of Letters Patent No. 324,623, dated August 18, 1885.

Application filed June 4, 1885. (No model.)

To all whom it may concern:

Be it known that I, J. HILL WHITING, of Detroit, in the county of Wayne and State of Michigan, have invented new and useful Im-
5 provements in Cupola-Furnaces; and I do hereby declare that the following is a full, clear, and exact description thereof, reference being had to the accompanying drawings, which form a part of this specification.

10 This invention relates to a new and useful improvement in cupola-furnaces, of which the following is a specification.

15 My invention consists in the peculiar and novel construction and arrangement of the tuyeres, which, instead of directing the blast in a concentrated form into the furnace, as in the present arrangement, diffuse it over the entire area of the cross-section of the cupola-furnace, all as hereinafter described.

20 In the accompanying drawings, Figure 1 is a vertical central section of a cupola-furnace provided with my improved tuyeres. Fig. 2 is a horizontal section on line $\alpha\alpha$.

25 A represents an ordinary cylindrical cupo-
la-furnace, the base of which is surrounded by a jacket, B, usually formed of cast-iron plates. This jacket forms an air-chamber, C, into which the blast from the blower is conducted through a suitable pipe, D, and which serves as a res-
30 ervoir from which the blast is distributed into the tuyeres.

35 F are the usual series of tuyeres, occupying the usual positions; but in size and shape they are different from the ordinary form, and are constructed as follows: The inlet-opening a of each tuyere is of the usual area, but instead of contracting more or less toward the discharge-opening b , as in the usual form, the tuyeres are made flaring, as shown, so that
40 their side walls become more or less tangential to the inner circle of the cupola. In vertical section these tuyeres are also more or less of a flaring shape, but not quite so much as in horizontal section. The inner ends, b , of the tuyeres are shaped circularly, so as to be flush with the inner face of the wall of the cupola.

45 I use a sufficient number of such tuyeres to

bring the whole, or nearly the whole, area of the cross-section at the discharge end of the tuyeres under the direct action of the blast 50 from the tuyeres, so that no dead-air spaces of any amount are left between the tuyeres.

With my diffusing-tuyeres more air is properly consumed in a given time, while the melting process takes place more evenly over 55 the whole area of the cross-section of the cupola.

In practice I have found that where it is an object to get iron of great fluidity that is rich in carbon my diffusing tuyeres accomplish a 60 much better result than the tuyere in ordinary use, which, on account of their form, are liable to concentrate the blast too much in the center of the cupola and burn the iron, technically speaking—that is, deprive it of some 65 of its carbon.

It is clear that the blast-reservoir assists the flaring tuyeres to produce a more diffused blast.

I am aware of the Patents Nos. 240,136 and 70 290,343, and make no claim to anything shown therein as forming part of my invention.

I deem it important that the mouth of each tuyere is opposite the rib which forms the dividing-line between two tuyeres upon the op- 75 posite side, whereby the injected streams are forced diagonally across each other to thor-oughly mix the gases.

What I claim as my invention is—

In a cupola-furnace, the combination, with 80 the furnace A and jacket B surrounding the same and forming an air-chamber, C, of the rectangular tuyeres F, each enlarging from its inlet to its outlet, and arranged, as shown, with a small rib, a' , between each two adjacent 85 tuyeres, and the mouth of each tuyere opposite the rib between two other tuyeres, whereby the blast entering through said tuyeres is diffused over the whole sectional area of the cupola, substantially as described.

J. HILL WHITING.
